UNITED STATES PATENT OFFICE.

JOSEPH H. FREDRICH AND CHARLES BOCK, OF SAN FRANCISCO, CALIFORNIA.

TOY VEHICLE.

1,426,171.

Specification of Letters Patent. Patented Aug. 15, 1922.

Application filed October 17, 1921. Serial No. 508,090.

To all whom it may concern:

Be it known that we, JOSEPH H. FREDRICH and CHARLES BOCK, citizens of the United States, residing at San Francisco, in the 5 county of San Francisco and State of California, have invented new and useful Improvements in Toy Vehicles, of which the following is a specification.

This invention relates to improvements in 10 toy vehicles and has for its principal object to provide a device made to represent a horse or other animal equipped with movable legs adapted to engage the ground or floor, so as to propel the device and simulate 15 a horse in the act of walking, the legs being actuated by the rocking movement imparted to the horse by the rider thereon.

A further object of this invention is to 20 provide means on the legs of the device, which will tend to prevent the device being thrown off balance with a consequent danger 25 of injury to the one propelling the device.

A further object is to provide buffer means 25 on the body of the horse adapted to prevent a jarring sound and serving to make the contact of the legs with the body comparatively noiseless.

A still further object of this invention is 30 to provide a device of the character described which is simple in construction, economical to manufacture, positive in operation and a device which can be readily assembled and disassembled when occasion may demand.

35 Other objects and advantages will be apparent during the course of the following description.

In the accompanying drawings forming 40 a part of this specification, and in which like numerals are employed to designate like parts throughout the same,

Fig. 1 is a side elevation of a toy horse embodying my invention,

Fig. 2 is a transverse vertical section 45 through the body of the horse, the view being taken on the line 11—11 of Figure 1,

Fig. 3 is a perspective view of the front legs of the device, and

Fig. 4 is a detail perspective view of the 50 rear legs of the device with parts of the legs being broken away.

In the accompanying drawings wherein for the purpose of illustration is shown a preferred embodiment of our invention, the 55 numeral 5 designates as a whole the body of the device, which simulates the body of a

horse. This body consists of a top board 6, a bottom board 7, side walls 8, a front wall 9, and a rear connecting strip 10 all conventionally connected. To the front wall 9 there is secured the head portion 11 made to 60 represent the head of a horse. As shown to advantage in Figure 1 the bottom is slotted or open as at 12 adjacent the front of the device, and slotted as at 13 adjacent the rear 65 of the body. On the top board 6 there are positioned a hand hold 14 and a projection 16, which latter element simulates the rear end of a saddle.

Adapted to be received within the body 70 through the opening 12, is a pair of front legs 17, the legs being pivoted to the side walls 8 by a bolt 18, which is straddled by a reenforcing block 19, while the legs are connected to each other adjacent the upper 75 extremities of the same by a cross bolt 20. This construction serves to make the two front legs move in unison.

Adapted to penetrate the opening 13 adjacent the rear of the body is a pair of rear 80 legs 21. These legs are connected to each other by a cross pin 22 and are pivoted to the body adjacent the rear end of the same by a pivot bolt 23 straddled by a block 24. The front legs 17 above referred to terminate 85 in tread portions 25 and are enlarged to simulate the horse's hoofs. By referring to Figures 1 and 2 it will be observed that rubber cleats 26 are disposed on the rear of the tread portions which are inclined as at 90

27. The cleats 26 serve as stops to frictionally engage the ground when the child on the horse imparts a rocking movement forward. When the child on the horse makes a rocking movement backward then the legs 95 will assume a substantially perpendicular position with relation to the ground, as shown in dotted line position in Figure 1. On the other hand, the rear legs 21 are likewise enlarged to present tread portions, but have cleats 28 positioned on the front of their tread portions and are inclined as at 29.

The purpose of these cleats is to allow the same to grip the ground and prevent the tread portions from being slid forwardly or rearwardly when the front feet 17 are being moved forward. The inclined portions 29 act as a safety means and serves to prevent the device being thrown off balance when the horse is rocked rearwardly.

Within the horse on the bottom wall 7 we have suitably mounted a standard 30.

A helical spring 31 connects the bolt 20 and the said standard. This spring is expanded when the horse is in the position shown in Figure 1 and returns to its normally contracted position when the horse assumes the dotted line position shown in the same figure. The spring likewise serves to limit the forward movement of the upper extremities of the leg 17. Connecting an eye bolt 32 secured to the rear of the front wall 9 and the bolt 22 positioned between the rear legs 21 is a second coil spring 33 of greater length than the first mentioned spring 31. The purpose of this second mentioned spring is to cause the legs 21 to take a forward movement or jumping effect, after the front legs 17 have assumed the dotted line position of Figure 1 and the rider has next rocked forwardly on the horse.

20 As shown to advantage in Figure 1 a suitable rod 34 is secured to the connecting strip 10 and suspended therefrom and has its free end terminating slightly above the ground surface upon which the feet of the horse rests. The purpose of this rod is to eliminate any possible danger of the device tending to fall backward when a backward rocking movement is given to the device by the rider thereon.

25 In order that the contact of the legs with the respective parts of the body and auxiliary connecting pieces may have a noiseless and non-jarring effect we have conveniently placed a plurality of buffers at the respective points of contact of the legs with the above mentioned parts. These buffers are shown to advantage in Figure 1 and are designated as a whole by the numeral 34.

30 From the foregoing description taken in connection with the accompanying drawing

it will be apparent that a rocking movement imparted forwardly and rearwardly to the body of the horse will push the device forward quickly, and then causing the four legs to be actuated, the device will simulate a 45 horse into the act of walking.

It is to be understood that the form of our invention herewith shown and described is to be taken as a preferred example of the same, and that various changes in the shape, 50 size and arrangement of parts may be resorted to without departing from the spirit of the invention or the scope of the subjoined claim.

Having thus described our invention, we 55 claim:—

A device of the character described, comprising a body simulating that of an animal, legs pivotally connected to said body and engageable with the ground for propelling the 60 device upon a rocking movement of a rider seated on said body portion, said legs terminating in enlarged end portions, and inclined to limit the rocking movement of a rider thereon, tension means connected separately to each pair of legs and to the body of the device for controlling the movement of the said legs, buffers positioned on said body and adapted to receive the impact of the legs, and auxiliary safety means secured 65 to the rear of the body, said means comprising a rod of a lesser length than the legs of the device and adapted to contact with the ground upon an extreme rearward rocking movement of the device. 75

In testimony whereof we affix our signatures.

JOSEPH H. FREDRICH.
CHARLES BOCK.
